UNITED STATES PATENT OFFICE.

FREDRICK W. MILLER, OF MUSKEGON, MICHIGAN.

WAGON.

No. 872,531.

Specification of Letters Patent.

Patented Dec. 3, 1907.

Application filed June 18, 1906. Serial No. 322,272.

To all whom it may concern:

Be it known that I, FREDRICK W. MILLER, a citizen of the United States, residing at Muskegon, in the county of Muskegon and State of Michigan, have invented new and useful Improvement in Wagons, of which the following is a specification.

My invention pertains to wagons, more particularly dumping wagons; and it has for one 10 of its objects to provide a wagon embodying such a construction that it may be turned with facility, and any one of the wheels may pass over an obstacle without racking or otherwise injuring the wagon as a whole.

15 Another object of the invention is the provision of a dumping wagon embodying a vertically swinging bottom, and means whereby the driver of the wagon is enabled to release the said bottom and is also enabled to 20 place and lock the bottom in its closed position without leaving his seat on the wagon.

Another object is the provision of a wagon comprising a body constructed with a view of carrying asphalt in such manner as to prevent 25 the escape of heat from the asphalt while it is *enroute* to the point of use.

Other advantageous characteristics of my invention will be fully understood from the following description and claims when the 30 same are read in connection with the accompanying drawings, forming part of this specification, in which:

Figure 1 is an elevation of one side of the wagon constituting the present and preferred embodiment of my invention, as the same appears when the hinged sideboard and end board of the body are secured in their upper position. Fig. 2 is a similar view of the opposite side of the wagon. Fig. 3 is a 35 front end elevation of the wagon; the same being shown with the arms V omitted. Fig. 3^a is a detail, inverted plan view illustrating the connections between the lower arm of the hand lever g' and the rock-shaft a'. Fig. 4 is a transverse section taken in the plane indicated by the line 4—4 of Fig. 1, looking 40 forwardly, and illustrating all of the parts in front of the said plane; the arms V being omitted. Fig. 5 is a detail view showing the 45 manner in which the hinged end board and the hinged side boards of the body are secured together when the same are in their upper positions. Figs. 6 and 7 are detail 50 sections illustrating the arrangement of the

king bolt in the front axle of the wagon. Fig. 8 is a top plan view of the wagon with the side boards of the body closed down upon the upper edges of the body.

Similar letters designate corresponding parts in all of the views of the drawings, referring to which:

A is the rear axle of the wagon. B is a bolster fixed thereon.

C is the front axle.

D is a bolster disposed above the front axle.

E is the wagon body which is arranged on and fixedly connected to the bolsters B and D and serves to connect the said bolsters together.

F is a bowed and slotted plate disposed under and fixedly connected to the front axle C and having a longitudinal slot a.

G is a metallic brace fixedly connected to the front end wall of the body E and having a rearwardly extending lower portion b, Figs. 6 and 7, disposed under the bowed plate F.

H is a central socket fixed on the upper side of the front axle C above and in communication with a slot c in said axle.

I is a ball fixed on the under side of the front bolster D and disposed and adapted to move in the socket H, and J is a bolt extending downward through the bolster D, ball I, socket H, slot c in the axle C, slot a in the bowed plate F, and the rearwardly extending portion b of the brace G, and secured below the said brace portion b through the medium of a nut d or any other means compatible with the purpose of my invention.

By virtue of the construction thus far described, it will be apparent that the front axle C is free to swing horizontally toward the right or toward the left to facilitate turning of the wagon, and it will also be apparent that any one of the wheels on the axle may be raised as in passing over a stone or other obstacle in its path without racking or twisting or in any other way subjecting the wagon to undue strain. This will be better appreciated when it is noticed that in the event of one of the front wheels being raised, the axle C and the socket H will move on and with respect to the king bolt J and the ball I, respectively, and in the event of one of the rear wheels being raised the ball I and the king bolt J will move in and with respect to

the socket H and the axle C, respectively. When the wagon is on a level and the front axle C is swung horizontally in one direction or the other, the socket H will turn about the ball I, and the axle C and bowed plate F will turn about the king bolt J. It will further be apparent that the novel connection between the front bolster D and the front axle C is a strong and durable one and is well adapted to withstand the rough usage to which freight-carrying wagons are ordinarily subjected.

The body E of the wagon may be of any shape and construction compatible with the purpose of my invention without involving a departure from the scope thereof, though I prefer to have it comprise lower vertical side walls e, upper vertical side walls f, intermediate oblique side walls g which decline inward from the walls f to the walls e, a rear end wall h disposed vertically and fixed to the side walls, a front end wall k disposed vertically and fixed to the side walls and bearing a step l, false end walls m and n, see dotted lines in Figs. 1 and 2, which are arranged between the side walls and decline inward or toward the transverse center of the body, and a bottom wall p. This latter is hinged to one side wall of the body, preferably the right hand side wall, and is designed to be held up against the lower edge of the other side wall. It is also designed when released to gravitate to a vertical, pendent position so as to permit the contents of the body to drop therefrom. I prefer to effect the hinge connection of the bottom p in the manner best shown in Figs. 1 and 4—that is to say, through the medium of a longitudinal rod q disposed under the right hand side wall and arranged in straps r depending therefrom, and straps s connected to the bottom p and receiving the said rod q. On its under side and adjacent to its free or swinging longitudinal edge the bottom p is provided with a loop or eye t, Figs. 2 and 4, for a purpose which will be presently pointed out.

K is the driver's seat of the wagon, which is preferably of a special construction for a purpose presently pointed out.

L, Figs. 2, 3 and 4, is the mechanism for holding the bottom p in its closed position and for enabling the driver on the seat K to release the bottom whenever he desires to discharge the load of the wagon, and M, Figs. 1, 3 and 4, is the mechanism through the medium of which the driver on the seat K is enabled to raise the bottom p to its closed position precedent to securing the bottom p in said position by operating the mechanism L. The mechanism L comprises one or more, preferably three, vertical rock shafts u which are journaled in bearings on the side wall of the body and have inwardly directed arms v at their lower ends designed to rest below the free or swinging

portion of the bottom p and outwardly directed arms w at their upper ends, a longitudinal rod x connecting the arms w of the several rock shafts u, a hand lever y fulcrumed at an intermediate point of its length at one side of the forward portion of the body E and having its upper end arranged within convenient reach of the driver on the seat K, and a link z interposed between and connecting the lower arm of the lever y and the forward end of the rod x. With the parts in the position shown in Fig. 2, it will be apparent that the lower arms v of the rock shafts u will rest under the swinging portion of the bottom p and preclude casual downward movement of the said bottom. When, however, the upper arm of the lever y is swung toward the rear, it will be seen that the rock shafts u will be turned on their axes so as to move the arms v outward beyond the swinging edge of the bottom p, when the said bottom will be released and will swing down into a vertical position at one side of the body E so as to permit the contents of the said body to freely drop out of the same.

The mechanism M comprises a longitudinal rock shaft a' journaled in suitable bearings at the right hand side of the body E and having an upwardly disposed arm b' at its forward end and also having a lateral arm c', Fig. 4, at its rear end which lateral arm c' terminates in a hook d' permanently engaged with the loop or eye t on the bottom p, a horizontally swinging bell crank e', Figs. 1, 3, 3^a and 4, fulcrumed on the forward portion of the body E at the right hand side thereof, a link f' connecting the forwardly extending arm of the said bell crank and the arm b' of the rock shaft a', a lever g' fulcrumed at the right hand side of the forward portion of the body and having its upper arm arranged within convenient reach of the driver on the seat K, and a link h' connected to the lower arm of the said lever g' and connected to the outwardly extending arm of the bell crank e' at e' in Figs. 1 and 3^a. As shown in Fig. 1, the intermediate portion of the bell crank e' is preferably bent slightly upward so that said intermediate portion rests in a plane above the ends of the bell crank. With the parts in the position shown in Fig. 1, the bottom p is secured in its closed position, and when the said bottom is released and falls as before described the upper arm of the lever g' is moved toward the rear, and the lower arm of said lever g' is moved forward. Now when it is remembered that Fig. 3^a is an inverted plan view and that the link h' is connected to the lower arm of lever g' it will be seen that when the upper arm of said lever g' is moved forward and the lower arm thereof rearward, the bell-crank e', Fig. 3^a, will be swung on pivot e' in the direction of the arrow on the long arm of the bell-crank, the

link f' will be drawn endwise in the direction of said arrow, and the rock-shaft a' will be rocked in the direction of the arrow on said shaft with the result that through 5 the medium of the rear arm c' on rock-shaft a' , Fig. 4, the bottom p will be raised to its closed position. Now while the bottom p is in the latter position the driver on the seat K moves the upper arm of the lever y 10 forward, when as will be readily apparent the lower arms v of the rock shafts u will be caused to assume positions below the swinging edge of the bottom p so as to securely fasten the said bottom p in its closed position 15 and in that way preclude casual discharge of the load from the wagon.

It will be gathered from the foregoing that not only is the driver on the seat K enabled to release the bottom p to discharge 20 the load and then raise the said bottom p to and secure it in its closed position, but he is enabled to perform the said operations quickly and with the expenditure of but a minimum amount of effort. It will also be 25 gathered that the bottom raising mechanism and the bottom securing and releasing mechanism are simple and durable, and afford considerable leverage so that the driver has but to expend little effort in raising 30 the bottom p and in securing and releasing the said bottom. In this latter connection it will be noticed that when the wagon is loaded and it is desired to discharge the load, the driver has but to withdraw 35 the arms v of the rock shafts u from under the bottom p when the weight of the load will immediately cause the said bottom p to assume its pendent and fully open position.

40 N is a horizontal board arranged under and carrying the driver's seat K and connected at its forward edge to the forward end of the body E through the medium of a hinge P whereby the said board N is adapted 45 to swing upward and forward on the body E so as to permit of asphalt or other material being readily placed in the forward portion of said body E . Q is a ledge fixed to and extending rearwardly from the said board N , 50 and R is the front end board while S is the rear end board and T the side boards which form an upward extension on the body E and in that way contribute materially 55 to the capacity of the wagon for carrying grain, coal and similar material in bulk. The front end board R is fixed to the rear edge of the board N and is movable with said board N on and off the body E for the purpose before described. The rear end 60 board S is hinged to the rear end wall h of the body E while the side boards T are hinged at U to the upper edges of the side walls of the said body E . When the side boards T are swung upwardly and outwardly 65 to their open positions, it will be apparent

that arms V with which said side boards are provided will bring up against the outer sides of the upper portions of the side walls of the body and in that way assist in maintaining the said boards T in their open position. It 70 will also be seen that when the side boards T are open their forward ends will rest in keepers W on the front end board R , while hooks X on their rear ends will rest between cam-like protuberances Y on the rear end 75 board S , and upturned lugs Z provided at the extreme ends of said rear end board S . From this it follows that when the boards T and S are in their open positions there is no liability of any one of the said boards falling 80 outwardly. When, however, it is desired to disconnect the end board S from the side boards T , the same may be readily accomplished by swinging the side boards T inward to a vertical position when the upper edge 85 of the end board S will clear the ends of the hooks X , and said end board S may then be swung down into a pendent position at the rear end of the body. With this done the side boards T may be swung into a horizontal 90 position on the body E as shown in Fig. 8 so as to cover the said body E and in that way prevent the escape of heat from asphalt when the same is carried in the body.

When the wagon is employed to transport 95 asphalt or the like, it will be seen that after the asphalt has been discharged from the body E in the manner before described in detail, the side boards T and the end board S may be raised to an open position, and then 100 the hooks X on the side boards T may be moved outward over the cam-like protuberances Y on the end board S until they assume positions between said protuberances and the lugs Z when said side boards and rear end 105 board will be locked together without liability of either moving casually from its open position. Now when open the side boards T and end board S will obviously facilitate the placing of asphalt or other material in 110 the body E , and after the body E is fully loaded the said side boards may be closed over the body E for the purpose before stated. When the side boards T are closed as stated the before mentioned ledge Q on 115 the board N will serve to support the inner forward portions of the side boards.

I have entered into a detailed description of the construction and relative arrangement of the parts embraced in the present and 120 preferred embodiment of my invention in order to impart a definite understanding of the said embodiment. I do not desire, however, to be understood as confining myself to the said specific construction and relative 125 arrangement of parts as such changes or modifications may be made in practice as fairly fall within the scope of my invention as claimed.

Having described my invention, what I 130

claim and desire to secure by Letters Patent is:

1. In a dumping wagon, the combination with a body having a vertically swinging bottom; of a rock shaft disposed vertically in a bearing on the body and having an arm arranged to assume a position below the swinging portion of the bottom, and also having an arm through the medium of which 10 it may be rocked.
2. In a dumping wagon, the combination with a body having a vertically swinging bottom; of a lever mounted on the body, a rock shaft disposed vertically in a bearing on 15 the body and having an arm arranged to assume a position below the swinging portion of the bottom and also having an arm extending in an opposite direction with respect to the first mentioned arm, and a connection between the second mentioned arm of the rock shaft and the lever.
3. In a dumping wagon, the combination with a body having a vertically swinging bottom; of a lever mounted on the body, 20 rock shafts disposed vertically in bearings on the body at intervals in the length thereof and having lower arms arranged to assume positions below the swinging portion of the bottom and also having upper arms extending 25 in an opposite direction with respect to the first mentioned arms, and connections between the upper arms of the rock shafts and the said lever.
4. In a dumping wagon, the combination 30 with a body having a vertically swinging bottom hinged to one of its sides; of a lever mounted on the body, rock shafts disposed vertically in bearings on the side of the body at intervals in the length thereof and having rearwardly and inwardly extending arms 35 at their lower ends and rearwardly and outwardly extending arms at their upper ends, a rod connecting the upper arms of the several rock shafts, and a connection between 40 the said rod and the lever.
5. In a dumping wagon, the combination 45 of a body having a vertically swinging bottom provided adjacent to its swinging edge with a loop or eye, a rock-shaft journaled on the body and having an arm disposed below the swinging bottom and terminating in a hook disposed in the loop or eye on said bottom, a lever, and a connection between the

lever and the rock shaft for moving the latter by the former.

55

6. In a dumping wagon, the combination of a body having a vertically swinging bottom hinged to it at one side, a movable device at the opposite side of the body adapted in one position to retain the bottom in its closed position, a manipulating device at the same side of the body connected with the said retaining device, a bottom raising device at the side of the body adjacent to the hinge of the bottom, a manipulating device at the same side of the body, and a connection between said manipulating device and the bottom raising device.

60

7. In a wagon, the combination of a body, side boards hinged to swing inward and outward on the body and having hooks extending longitudinally from the upper portions of their ends and then downward, and an end board hinged to and arranged to swing on the body at a right angle to the direction of movement of the side boards and having cam-like protuberances on its upper edge adjacent to its ends and also having upturned lugs at its ends; the said end board being also arranged when in its raised position to rest within the hooks on the side boards and with its cam-like protuberances at the inner sides of the longitudinally extending portions of said hooks.

65

8. In a wagon, the combination of a body, 70 a seat board hinged to the forward end of the body so as to swing upward and forward therefrom, a front end board fixed to and extending up from the rear portion of the seat board and having keepers at its ends, 75 side boards hinged to the body and having hooks on the upper portions of their rear ends, and an end board hinged to the body and having cam-like protuberances on its upper edge adjacent to its ends and also having upturned lugs beyond the outer ends of the protuberances.

80

85

In testimony whereof I have hereunto set my hand in presence of two subscribing witnesses.
